Inventor:

Gustaf A. Gustafson,
5 by Robert Burns
Attorney.

UNITED STATES PATENT OFFICE.

GUSTAF A. GUSTAFSON, OF CHICAGO, ILLINOIS.

AUTOMATIC REGULATOR.

No. 839,134.

Specification of Letters Patent.

Patented Dec. 25, 1906.

Application filed December 6, 1905. Serial No. 290,523.

To all whom it may concern:

Be it known that I, GUSTAF A. GUSTAFSON, a citizen of the United States of America, and a resident of Chicago, in the county of Cook and State of Illinois, have invented certain new and useful Improvements in Automatic Regulators, of which the following is a specification.

This invention relates to that type of smoke-consumers for steam-boiler furnaces in which a jet of air, or air and steam combined, is discharged into the combustion-chamber of the furnace to prevent the formation of smoke during and immediately succeeding the firing operation; and the present invention has for its object to provide a simple and efficient automatic controlling mechanism by means of which the above functions are effected in a certain and automatic manner, all as will hereinafter more fully appear, and be more particularly pointed out in the claims.

In the accompanying drawings, Figure 1 is a front elevation of a steam-boiler furnace having the present improvement applied. Fig. 2 is a side elevation, with parts in section, of the same. Fig. 3 is an enlarged detail section of the oscillating holder by which the operation of the furnace-jets is controlled. Fig. 4 is an enlarged detail section of one of the furnace-jets. Fig. 5 is a detail plan view of the furnace fire-door, showing the operating-lugs of the present mechanism.

Similar numerals of reference indicate like parts in the several views.

Referring to the drawings, 1 represents the steam-boiler furnace, of any usual construction; 2, its front wall, and 3 its fire door or doors, hinged in place, as usual.

4 represents the usual series of inclined blower-jets located in the front wall of the furnace above the fire-doors and adapted to discharge jets of air, steam, or air and steam combined in an inclined direction onto the fuel. Any usual type of such jets may be used. It is, however, preferable to use air and steam combined, and accordingly such type of jet is shown in the accompanying drawings.

5 is an open-ended air-supply pipe communicating with the jets 4.

6 is a steam-supply pipe arranged within

said air-supply pipe and connected with the jets 4 aforesaid.

7 is a controlling-valve in the steam-pipe 6 and preferably of the balanced type, so as to be easy of operation by the automatic mechanism hereinafter described.

8 is a stationary bracket secured to the furnace-front and affording bearings for the automatic mechanism now to be described.

9 is an elongated vessel or holder having trunnions 10 at its mid-length by which pivotal support is had in the brackets 8 aforesaid. Such holder 9 is preferably enlarged 65 at each end, as shown, and is adapted to contain a body of water, mercury, or like fluid, as common in this type of devices.

11 is a valve-seat arranged midway the length of the holder 9 and dividing the same 70 into two compartments, as shown in Fig. 3. 12 is a check-valve closing a large orifice in said seat 11 and permitting a rapid flow of the fluid from one end to the other of the holder 9 in one direction.

13 is a small opening formed either in the valve 12 or seat 11 and through which the flow of the fluid in an opposite direction to that above mentioned takes place in a retarded manner, and with a view to regulate 80 such retardation of the flow the area of said opening 13 can be adjusted in any usual and well-known manner, as the judgment of the constructor may deem best.

14 is a vent pipe or passage connecting the 85 respective ends of the holder 9 together to permit of a flow of the contained air from one end to the other of the holder in the continued practical operation of the apparatus.

15 and 16 are crank-arms on the trunnions 90 10 aforesaid and arranged substantially at an angle of ninety degrees to each other, as shown.

17 is a rod or bar operatively connecting the crank-arm 15 and the valve 7 together.

18 is a rod or bar operatively connecting the crank-arm 16 with a bell-crank lever hereinafter described.

When so desired, the respective rods 17 and 18 may be provided with any usual 100 means of longitudinal adjustment in order that the timing of the parts may be regulated after assembly.

19 is a bell-crank lever pivoted on the hori-

zontal pivot-rod 20 of a bracket secured to the furnace-front and having a depending arm 21, ending in a lateral finger 22 for operative engagement with the fire-door 3, as 5 hereinafter described.

23 is a cushion-spring upon the pivot-rod 20 and to one side of the bell-crank lever 19 for yieldingly holding said lever to its engagement with the fire-door.

10 24 represents a pair of lugs arranged in separated relation on a hinge-eye of the fire-door 3 to form a receiving-recess in which the lateral finger 22 of the bell-crank lever 19 aforesaid has operative engagement, so that 15 the opening and closing of said fire-door will impart corresponding movements to said lever and its accessories.

The operation of the mechanism is as follows: Normally the valve 7, controlling the 20 supply of steam to the furnace-jets, is closed.

With the opening of the fire-door 3 to add 25 fresh fuel, &c., movement is communicated by said fire-door to the bell-crank lever 19, and through the instrumentality of the connecting-rod 18 and crank-arm 16 the holder 9 is partly oscillated and its forward end depressed to a point below a horizontal line, and in unison with such movement the crank arm 15 causes an opening of the valve 7. The 30 fluid in said holder then flows by gravity into the forward end of the chamber without any impedance from the check-valve 12, and in consequence a rapid descent of the forward end of said holder takes place. Such de-

35 scending movement of the forward end of the holder takes place independent of the rod 18, and its connections by the provision of the elongated slot 18" in said rod, as shown in Fig. 2. With a closing of the fire-door movement in a reverse direction is communicated 40 from said fire-door to the bell-crank lever 19, and through the instrumentality of the connecting-rod 18 and crank-arm 16 the holder 9 is partly oscillated to raise its forward end 45 to a point above a horizontal level. The fluid in the forward part of said holder now flows in a slow or retarded manner through the contracted opening 13 into the rear end of the holder 9 to effect a slow descent of the 50 rear end of said holder and a corresponding slow closure of the controlling-valve 7 and a stoppage of the action of the furnace-jets 4.

Having thus fully described my said invention, what I claim as new, and desire to 55 secure by Letters Patent, is—

1. In an operating mechanism for the pressure-supply valve of smoke-consumers and the like, the combination of a fixed support, a tilting holder containing a fluid body and 60 having trunnions midway its length by which it is journaled in said support, a check-valve and seat arranged centrally in said holder to divide the same into a pair of end chambers, means for affording a restricted communica-

tion between said chambers, an air pipe or 65 passage connecting the tops of said chambers together, a pair of crank-arms arranged at right angles to each other on the trunnions of the holder, a pressure-supply valve having a link connection with one of said crank-arms, 70 an operating-rod having an elongated slot connection with the other crank-arm, and means for imparting reciprocation to said rod.

2. In an operating mechanism for the pressure-supply valve of smoke-consumers and the like, the combination of a fixed support, a tilting holder containing a fluid body and having trunnions midway its length by which it is journaled in said support, a check-valve 80 and seat arranged centrally in said holder to divide the same into a pair of end chambers, means for affording a restricted communication between said chambers, an air pipe or passage connecting the tops of said chambers 85 together, a pair of crank-arms arranged at right angles to each other on the trunnions of the holder, a pressure-supply valve having a link connection with one of said crank-arms, an operating-rod having an elongated slot 90 connection with the other crank-arm, a furnace-door having lugs on its pintle-ears, and an intermediate bell-crank lever having engagement with said lugs and with the operating-rod aforesaid.

3. In an operating mechanism for the pressure-supply valve of smoke-consumers and the like, the combination of a fixed support, a tilting holder containing a fluid body and having trunnions midway its length by which it is journaled in said support, a check-valve and seat arranged centrally in said holder to divide the same into a pair of end chambers, means for affording a restricted communication between said chambers, an air pipe or 100 passage connecting the tops of said chambers together, a pair of crank-arms arranged at right angles to each other on the trunnions of the holder, a pressure-supply valve having a link connection with one of said crank-arms, 105 an operating-rod having an elongated slot connection with the other crank-arm, a furnace-door having lugs on its pintle-ears, and an intermediate bell-crank lever connected to the operating-rod aforesaid and provided 110 with a lateral finger for engagement with said lugs.

4. In an operating mechanism for the pressure-supply valve of smoke-consumers and the like, the combination of a fixed support, a tilting holder containing a fluid body and having trunnions midway its length by which it is journaled in said support, a check-valve and seat arranged centrally in said holder to divide the same into a pair of end chambers, 120 means for affording a restricted communication between said chambers, an air pipe or passage connecting the tops of said chambers

together, a pair of crank-arms arranged at right angles to each other on the trunnions of the holder, a pressure-supply valve having a link connection with one of said crank-arms, 5 an operating-rod having an elongated slot connection with the other crank-arm, a furnace-door having lugs on its pintle-ears, an intermediate bell-crank lever having engagement with said lugs and with the operating-

rod aforesaid, and a spring for holding said 10 lever to its engagement with said lugs.

Signed at Chicago, Illinois, this 2d day of December, 1905.

GUSTAF A. GUSTAFSON.
